UNITED STATES PATENT OFFICE

FRANK RYGL, OF NEW YORK, N. Y.

EXTENSION TABLE TOP

Application filed April 28, 1928. Serial No. 273,575.

This invention relates to furniture, and has particular reference to an improvement in extension tops for tables. The invention primarily comprehends an extension table top which includes a main stationary top section and extension leaf sections which are connected to the marginal edges of the main section for swinging movements respectively to an extended position in a plane 5 with the main section and to a folded out of the way position underlying the main section.

The invention furthermore comprehends in an extension table top of the character set forth a connection between the leaf sections to cause simultaneous movements thereof whereby when one extension leaf section is moved to an open position or vice versa the remaining sections are moved therewith, 15 thereby avoiding the necessity of independently moving the sections.

As a further object, the invention embodies a means for simultaneously locking and rigidly supporting the extension leaf sections in their extended position, which means is operable from any side of the table.

The invention further resides in the provision of a stationary table top and drop leaves therefor which are constructed in such a manner that when not in use, the drop leaf sections are moved to a point where they will not interfere with the knees of persons seated at the table and further arranged in such a manner that two or more of said tables may be brought together with their marginal edges in contact.

The invention furthermore comprehends a means for normally retaining the extension leaf sections or drop leaves in a folded out of the way position underlying the main section so as to prevent accidental movement or swinging of said leaves either when the table is at rest or being transported.

Other objects of the invention reside in the comparative simplicity of construction and mode of use, the economy with which the table top may be produced and the general efficiency derived therefrom.

With the above recited and other objects in view, reference is had to the following

description and accompanying drawings, in which there is exhibited one example or embodiment of the invention, while the claim defines the actual scope of the same.

In the drawings:

Figure 1 is a perspective view of a table equipped with an extension top constructed in accordance with the invention and illustrating the extension or drop leaves in their set up or extended condition.

Figure 2 is an enlarged inverted sectional plan view of the top taken approximately on the line indicated at 2-2 in Figure 3.

Figure 3 is a transverse sectional view taken approximately on the line indicated at 3-3 in Figure 2.

Figure 4 is an inverted sectional plan view similar to Figure 2 but illustrating the leaves in folded condition.

Figure 5 is a transverse sectional view taken approximately on the line indicated at 5-5 in Figure 4.

Referring to the drawings by characters of reference, 6 designates the main stationary top section of the table which is supported from the head 7 of the pedestal 8 by a plurality of column or standard sections 9. An extension or drop leaf section 10 is connected to each of the marginal edges of the main stationary top section, preferably by hinges 11, which permit the leaves to swing from an extended position in a plane with the main top section to a folded out of the way position underlying said main section or vice versa. In order that the connected edges of the leaves will be disposed wholly within the marginal edges of the top section, the said connected edges of the leaf sections are chamfered or beveled as at 12 while the marginal edges of the main section are correspondingly chamfered or beveled as at 13. The leaves 10 are connected to each other for simultaneous movements by means of links 14 which are fulcrumed at their outer ends as at 15 to the leaves and fulcrumed as at 16 at 95 their inner ends to a rotary element 17 which is mounted for turning movement on a depending stud 18 anchored to and projecting downwardly from the center of the main stationary top section 6. A coiled contractile

spring 19 or its equivalent is connected at one end to the rotary element and is anchored at its opposite end to one of the standard sections 9 for the purpose of normally swinging and maintaining the leaves 10 in their folded out of the way position underlying the main table top section 6 and further for tensioning the movement of the leaves from said folded position to the extended position. This, obviously, prevents accidental movement of the leaves from their folded condition when the table is at rest or being carried.

In order to provide a means for locking and rigidly supporting the leaf sections in their extended position, a plurality of radial lock bars 20 corresponding in number to the number of leaves are attached to a center piece 21 which is mounted for turning movement on the stud 18 between the rotatory element 17 and the under side of the main stationary top section 6. The lock bars 20 are turntable from an inactive position within the confines of the main stationary top section to an active position projecting beyond the marginal edges and under the leaves 10 when the leaves are in their extended position and are designed to engage with keeper elements 22 and 23 on the under surfaces of the leaves and main stationary top section 6.

From the foregoing, it will thus be seen that an improved extension top for tables has been devised in which the drop leaves are connected for simultaneous movement from an opened to a closed position or vice versa and in which means is provided for rigidly holding the leaves in folded condition against accidental movement and for rigidly locking the leaves in extended or opened condition.

What is claimed is:

An extension table top including a main stationary top section and leaf sections connected to the marginal edges of the main section for movements respectively to an extended position in a plane parallel with said main section and to a folded out of the way position underlying the main section, a connection between said leaf sections to cause simultaneous movement thereof, means for locking and rigidly supporting said leaf sections in their extended position, said means comprising a member mounted for turning movement on the under side of the central portion of the main top section and radial arms turnable therewith from an inactive position within the confines or area of the main top section to an active position projecting beyond the marginal edges of the main top section and underlying the leaves and keepers provided respectively on the under side of the leaves and the under side of the main table top section.

Signed at New York, in the county of New York and State of New York this 27th day of April A. D. 1928.

FRANK RYGL.
